ADVERTISING DEVICE FOR PENCILS OR THE LIKE

Harry W. Brewer, St. Louis, Mo., assignor to Rite-point Co., St. Louis, Mo., a corporation of Missouri

Application May 16, 1947, Serial No. 748,549

2 Claims. (Cl. 40—126)

1

This invention relates to an advertising device adapted to be mounted and supported on an end of a pencil, fountain pen, or the like.

Primarily, it is an object of the invention to incorporate on an end of a pencil, pen, or similar device, attractive means for displaying advertising matter simulating paste or cream extruding from a tubiform container.

Another object of the invention is to provide on an end of a pencil, pen or the like, a novel moving attention-directing device whereby an observer's eye is quickly attracted to advertising matter on the device.

Other objects of the invention, which are not particularly enumerated, will become apparent, as the description of the device proceeds.

While the invention is defined in the appended claims, the following detailed description of the invention, when taken in connection with the accompanying drawing, will disclose the invention, its construction and use.

Fig. 1 is an elevational view of a pencil embodying the invention which simulates a paste or cream tubiform container.

Fig. 2 is an inverted view thereof showing an attention-directing rod which is in extruded position,

Fig. 3 is a top view thereof.

Fig. 4 is a vertical view of the same on an enlarged scale showing the rod in the position shown in Fig. 1, and

Fig. 5 is a vertical view of the same on an enlarged scale showing the rod in the position shown in Fig. 2.

In the drawing, a preferred embodiment of the invention is shown for purposes of illustration. A tip or cap, embracing the elements of the invention and shown in full lines on the drawing, is mounted on a barrel 10 of a pencil which is shown in dotted lines and is of conventional structure. The cap comprises a casing 11 which is mounted on the upper end of the barrel 10 and which contains a movable device that attracts the eye.

The casing 11 may be composed of a material such as a plastic of the same composition as the barrel 10, and is attached to the barrel 10 by means of a threaded member 12 which is screwed into the lower end of the casing 11 by external threads 13. The external threads 13 on the member 12 and internal threads 14 on the barrel 10 attach and mount the cap on the pencil.

The casing 11 with its end piece or head 15 simulates a paste or cream tubiform container

preferably of a particular commercial article, and a lip portion 16 extending outwardly beyond the end member or head 15 simulates the threaded end of such a container. An aperture 17 which is fashioned in the head 15 and the lip 16 passes a rod 18 which slidably moves in the aperture to simulate a paste or cream extruding from a tubiform container.

The lower or inward end of the rod 18 has a stop portion 19 which retains the rod 18 in the position shown in Fig. 2. The stop 19 is made sufficiently large enough to retain the rod 18 in the aperture 17 at all times.

The rod 18 operates in the aperture 17 by gravitational forces depending upon the position of the pencil. When the pencil 10 is inverted from the position shown in Fig. 1, the rod 18 moves out of the casing 11 and simulates extruding paste or cream. With the device in the position shown in Fig. 2 an inversion of the pencil 10 will move the rod 18 by gravity back into the casing 11.

The difference between the outer diameter of the rod 18 and the inner diameter of the aperture 17 is the determining factor as to the speed with which the rod 18 moves through the aperture 17. Although the clearance is enough to prevent binding between the parts, it is sufficiently close to produce a dash pot effect. The effect is produced by closing the casing 11 with the head 15 and the member 12 in order that the air needed to replace the space occupied by the rod, as it extrudes from the aperture 17 by gravity, can only enter or leave the casing 11 around the rod 18 through the aperture 17. Thus, it is apparent that the greater the difference in the diameters between the rod 18 and the aperture 17 the faster will be the movement of the rod 18, and the smaller the difference in diameters the slower the movement of the rod 18. It is also apparent that a dash pot effect may be produced by the stop 19 and the casing 11 acting as a piston and cylinder. The difference in the diameters between the stop 19 and the casing 11 will produce, as the diameter of the stop 19 is varied, different speeds and will act the same as the rod 18 acts in the aperture 17.

It can be seen from the foregoing description of the invention that the invention accomplishes its objects. The rod 18, as it falls slowly through the aperture 17 simulates a paste or cream, as the cream or paste would extrude from a particular tubiform container. Thus, an observer's eye is quickly attracted to the pencil, whose upper end with its casing 11, head 15 and lip portion 16,

takes the form and simulates the particular container. The observer's attention is then directed to the advertised simulated product whereby the product is thereby impressed upon his mind.

Various changes may be made in the details of construction of the device within the scope of the appended claims, without departing from the spirit of this invention. Parts of the invention may be used without the whole and improvements may be added while retaining some or all of the advantages of the invention.

What is claimed is:

1. An advertising device adapted to be mounted and supported at one end thereof by a pencil, pen, or the like comprising a casing simulating a paste or cream tubiform container, an end member simulating a top end portion of a paste or cream tubiform container on one end of said casing, said member having an end aperture, a rod simulating such paste or cream operating in said aperture, and a stop portion on the inner end of said rod to operate in said casing with the speed

of said rod operating in said aperture being controlled by the air pressure inside the casing.

2. An advertising device adapted to be mounted and supported at one end thereof by a pencil, pen, or the like, comprising a casing simulating a paste or cream tubiform container and having an aperture at the other end thereof, a rod simulating such paste or cream operating in said aperture to simulate a flow of such paste or cream therefrom, and controlling means to insure a slow movement of said rod.
